UNITED STATES PATENT OFFICE.

BAGSTER ROADS SEABROOK, OF WINNIPEG, MANITOBA, CANADA, ASSIGNOR, BY MESNE ASSIGNMENTS, TO LYRADION MANUFACTURING COMPANY, OF MISHAWAKA, INDIANA, A CORPORATION OF DELAWARE.

SOUND BOX.

Application filed May 2, 1919. Serial No. 294,292.

To all whom it may concern:

Be it known that I, BAGSTER ROADS SEABROOK, of the city of Winnipeg, in the Province of Manitoba, Canada, have invented 5 certain new and useful Improvements in Sound Boxes, of which the following is the specification.

The invention relates to improvements in sound boxes as used on talking and similar 10 machines and the principal object of the invention is to provide a non-sound absorbing sound box which will deliver the sound waves to the customary tone arm with great intensity and will not act to absorb a considerable proportion of the sound as occurs 15 in the present sound boxes of which I am aware.

A further object of the invention is to improve the suspension of the stylus bar.

20 With the above objects in view the invention consists essentially in the arrangement and construction of parts hereinafter more particularly described and later pointed out in the appended claim, reference being had 25 to the accompanying drawing in which:—

Fig. 1 represents a front view of the sound box.

Fig. 2 represents a vertical sectional view centrally through the same.

30 Fig. 3 represents a horizontal sectional view at X—X' Fig. 1.

In the drawing like characters of reference indicate corresponding parts in the several figures.

35 1 represents an outer casing provided centrally at the rear with an outlet tubular opening 2 and having the front side screw threaded to receive an annular metallic screw ring 3. To the back of the casing I 40 secure a metallic elbow 4 or ordinary form and provided with an outstanding attaching flange 5 which is connected to the back of the casing by fastening screws 6, there being a rubber gasket or washer 7 inserted between 45 the flange and the casing. The outlet 2 opens to the interior of the elbow.

On the entire inner face of the back wall of the casing 1, I apply a comparatively thick non-responsive, non-metallic and non- 50 absorbing layer or coating 8. To insure the firm holding of this composition, the casing may be roughened as indicated at 9, Fig. 3 so that the roughening actually extends into

the composition and gives a large adhering surface.

Directly in front of the layer of composition an annular paper-like ring may be placed which is first saturated in shellac under pressure. Next to this or even in contact with the composition there is placed two 60 elastic cushioning rings 11 and 12 between which I support the usual diaphragm 13 formed of any desired material. The various parts and the diaphragm are held in place by the screw ring 3 which holds them 65 securely in place between the inner face of this ring and the front face of the composition 8.

14 represents the stylus bar which has the inner end attached to the diaphragm and 70 the outer end pivotally attached to the bridge 17 which extends outward from the casing. The fulcrum of the stylus bar at 18 and 19 has conical recesses at the ends thereof into which the conical ends of screws 15 75 and 16 are seated.

20 and 21 represent tension springs permanently secured by means of screws 22 and 23 to the stylus bar so as to project transversely of the stylus bar fulcrum. The free 80 ends of the springs are provided with adjusting screws 24 and 25 which engage the underside of the casing and the bridge respectively and are provided with lock nuts 26. Obviously this mounting allows of the in 85 and out swinging of the stylus bar as provided for by the pivot pins and of the restraining of the swinging movement dependent on the adjustment given the springs through the screws 24 and 25. The stylus or 90 needle 27 is connected to the lower end of the stylus bar by a set screw 28 in the ordinary way.

When this sound box is in use the absorption of the sound by the wall of the 95 sound box is reduced to a minimum owing to the application of the non-responsive composition provided on the inner face of the casing recess consequently the sound waves are delivered from the sound box through 100 the elbow with great purity and truthfulness.

It may be explained that in existing sound boxes with which I am familiar, the inner 105 face of the metallic casing is directly exposed to the interior of the sound box and

- through the reflection of sounds therefrom and the resulting interference, absorbs, or in other words, subtracts a considerable portion of the purity of the sound produced in 5 the box by the movement of the diaphragm. This is obviously detrimental to the delivery of the sound waves from the sound box to the elbow and their subsequent progress into the attached tone arm.
- 10 What I claim as my invention is:—
- A sound box casing having a central opening therethrough and an annular flange pro-

jecting therefrom beyond said opening, a plurality of projections of the inner face of said casing, a plastic self-setting composition covering the said projections in a thick layer. 15

Signed at Winnipeg, this 26 day of April 1919.

BAGSTER ROADS SEABROOK.
